UNITED STATES PATENT OFFICE.

GUSTAVUS S. PERKINS, OF HARTFORD, CONNECTICUT.

PNEUMATIC DOOR-CHECK.

SPECIFICATION forming part of Letters Patent No. 294,905, dated March 11, 1884.

Application filed August 21, 1882. (No model.)

To all whom it may concern:

Be it known that I, GUSTAVUS S. PERKINS, of Hartford, in the county of Hartford and State of Connecticut, have invented a certain new and useful Improvement in Door-Checks, 5 of which the following is a description, reference being had to the accompanying drawings, where—

Figure 1 is a top view of my device as applied to a door. Fig. 2 is a view of same in longitudinal central section, showing the door open. Fig. 3 is a detail view of one end of the cylinder, the thumb-nut and washer removed to show the adjustable vent.

15 My invention relates to the class of devices for preventing the slamming of doors by the use of an air-cushion, and known as "pneumatic door-checks."

The invention consists in the new and improved combination of parts that renders the pressure of the spring practically uniform, whether the door is open or shut, gives a compact arrangement of operating parts, and renders the adjustable vent of the air-chamber 25 easily accessible when the door is closed.

In the accompanying drawings, the letter *a* denotes a cylinder, preferably of metal, as brass. *b* denotes a piston, usually leather-packed, and so fitted to the cylinder as to be air-tight; *c*, 30 a piston-rod fast to the piston at one end, and pivoted to the standard *d*, appurtenant to plate *e*, at the other. The cap *f* is recessed, as shown in Fig. 2, so that the cylinder fits closely upon the plate *e*, to which is pivoted the guide-rods *g*, which are pivoted at their outer end to the cap *h* of the cylinder. To the same cap, *h*, is pivoted the lever-arm *i*, which is also pivoted to the stand or bracket *k*, adapted to be secured to a door. The cap *h* is ordinarily fastened to the cylinder by a screw-thread, 40 and holds between them a leather disk, *l*, slotted for the admission of air to the cylinder, as through the opening *h'*, when the piston is drawn outward. Another opening, *h''*, is provided in cap *h*, closed by a thumb-nut, *m*, and this latter opening is used to adjust the outflow of air under pressure of the piston, which is impelled in closing the door by a coiled spring, *n*, arranged within the cylinder about 45 the rod, and bearing upon the cap and back of the piston.

My device is readily applicable to either a

right or left hand door, with no change in the parts herein shown, the plate *e* being fastened to the jamb over the door at a point near the hinge side, and the stand or bracket *k* to the upper edge of the door at a point farther removed from the hinge side.

By means of dotted lines in Figs. 1 and 2, I have illustrated the operation of the device 60 considered as a lever, the spring being the power applied between the pivot *e* on the plate *e* and the pivot *h'* on the bracket *k*. The short arm of the lever, from *e* to *x*, remains almost constant, as the door is swung open, while the 65 longer arm increases rapidly in length as the door is opened, as illustrated in Fig. 2, and the weight and friction of the door upon its hinges is also constant. At the same time the compression and resiliency of the coiled spring 70 have increased, with the result of a practically-uniform pressure upon the door at all points of its path between the extremes of open and shut—a desirable feature in many places.

By arranging the cylinder in the manner 75 shown, the air-chamber and its openings to the outer air are located on the outer end of the cylinder, with the adjustable vent covered by the thumb-nut in a position easy of access.

I am aware that pneumatic door-checks 80 consisting of the combination of the air-cylinder, levers, and brackets, and also having adjustable vents for governing the speed and force of closing the door, are not new, and these I do not broadly claim.

85 I claim as my invention—
1. In a pneumatic door-check, a cylinder, *a*, pivotally connected to guide-rods *g*, lever *i*, and bracket *k*, in combination with piston *b*, spring *n*, and rod *c*, pivoted to stand *e*, whereby the cylinder is reciprocated on the piston in opening and closing the door, all substantially as described, and for the purpose set forth.

2. In a pneumatic door-check, the combination of the cylinder *a*, having recessed head *f* and cap *h*, with vent *h'* and adjustable thumb-nut *m*, piston *b*, rod *c*, plate *e*, having standard *d*, guide-rods *g*, lever *i*, and bracket *k*, all substantially as described.

GUSTAVUS S. PERKINS.
